UNITED STATES PATENT OFFICE

170,621

CEDAR CHEST OR THE LIKE

Henry M. Barringer, Greensboro, N. C.

Application April 24, 1953, Serial No. 24,669

Term of patent 7 years

(Cl. D33—19)

To all whom it may concern:

Be it known that I, Henry M. Barringer, a citizen of the United States, residing at Greensboro, in the county of Guilford and State of North Carolina, have invented a new, original, and ornamental Design for a Cedar Chest or the like, of which the following is a specification, reference being had to the accompanying drawings, forming a part thereof.

In the drawings:

I claim:

The ornamental design for a cedar chest or the like, substantially as shown.

HENRY M. BARRINGER.
